(57) **CLAIM**
We claim the ornamental design for a panel attachment extrusion with key, as shown and described.

DESCRIPTION

FIG. 1 is a perspective view of a panel attachment extrusion with key showing our new design, in an assembled configuration of use;
FIG. 2 is a top view thereof;
FIG. 3 is a first side view thereof;
FIG. 4 is a second side view thereof;
FIG. 5 is a front view thereof;
FIG. 6 is a rear view thereof;
FIG. 7 is a bottom view thereof;
FIG. 8 is a perspective view thereof, shown in an exploded configuration;
FIG. 9 is a second perspective view thereof;
FIG. 10 is an enlarged view of the key portion of a panel attachment extrusion with key;
FIG. 11 is a top view thereof;
FIG. 12 is a first side view thereof;
FIG. 13 is a second side view thereof;
FIG. 14 is a front view thereof;
FIG. 15 is a back view thereof;
FIG. 16 is a bottom view thereof;
FIG. 17 is a perspective view of a second embodiment of a panel attachment extrusion with key;
FIG. 18 is a second perspective view thereof;
FIG. 19 is a top view thereof;
FIG. 20 is a first side view thereof;
FIG. 21 is a second side view thereof;
FIG. 22 is a front view thereof;
FIG. 23 is a back view thereof;
FIG. 24 is a bottom view thereof; and,
FIG. 25 is a perspective view thereof, shown in an exploded configuration.

The broken away symbols in the drawings indicate the appearance of any portion of an article between the break lines that forms no portion of the claimed design.

The broken lines and features shown in broken lines depict portions of the panel attachment extrusion with key that form no part of the claimed design.
